ROTARY PUMP

William Ward Davidson, Evanston, Ill.

Application August 4, 1940, Serial No. 351,359

21 Claims. (Cl. 230—146)

This invention relates to rotary pumps of the planetary type, that is, pumps in which a piston member has rotary movement with respect to a stationary member to produce a pumping action. The principal object of this invention is to provide a pump of this type which has exceptional efficiency and can be made at costs that are competitive with the present commercial forms of rotary and reciprocating pumps.

Further and other objects and advantages will become apparent as the disclosure proceeds and the description is read in conjunction with the accompanying drawings, in which

Fig. 1 is a vertical, sectional view showing a preferred form of the invention;

Fig. 2 is a horizontal, sectional view taken on the line 2—2 of Fig. 1;

Figs. 3, 4 and 5 are diagrammatic views showing successive positions of the piston member at 90° intervals in the pump cycle;

Fig. 6 is a horizontal, sectional view taken on the line 6—6 of Fig. 1;

Fig. 7 is a vertical, sectional view taken on the line 7—7 of Fig. 6 and showing particularly the intake valve arrangement;

Fig. 8 is a vertical, sectional view taken on the line 8—8 of Fig. 6 and showing particularly the discharge valve arrangement;

Fig. 9 is a fragmentary, perspective view partially in section, showing the support frame associated with the upper cylinder head;

Fig. 10 is a perspective view of the cylinder ring;

Fig. 11 is a perspective view looking down upon the lower cylinder head, the partition blade being shown in dotted lines;

Fig. 12 is a perspective view of the driver sleeve;

Fig. 13 shows the piston member with its integrally formed, upwardly extending shank which fits within the driver sleeve;

Fig. 14 is a perspective view of the rocker for the blade;

Fig. 15 shows the partition blade;

Fig. 16 is a vertical, sectional view showing a modification of the invention in which the piston member is provided with oppositely extending shanks to extend the bearing area;

Fig. 17 illustrates the preferred form of oil pump for use with the structure shown in Fig. 16;

Fig. 18 is a horizontal, sectional view taken on the line 18—18 of Fig. 16; and

Fig. 19 shows another type of oil pump which may be used with either the preferred embodiment of the invention shown in Fig. 1, or the modified form of the invention shown in Fig. 16.

The disclosure of selected preferred and modified forms of the invention is in compliance with Section 4888 of the Revised Statutes, but it should be understood that the appended claims are not to be limited by these specific disclosures unless required by the prior art.

General organization

By referring to Fig. 1, it will be seen that the 10 planetary pump A is supported by a frame B within a dome C, the pump being driven by a motor D, the rotor E of which rotates a driver sleeve F which in turn imparts planetary movement to the pump piston G through a shank H which is in telescopic engagement with the driver sleeve F. A partition blade I divides the pump chamber formed between the upper and lower heads of the pump cylinder into intake and discharge chambers so that each revolution of the 15 piston G discharges gas from the pump and simultaneously draws a new supply of gas into the pump for compression.

Main pump assembly

25 The main pump assembly (Fig. 1) consists of a stationary cylinder ring 20 preferably of nickel iron, to which upper and lower cylinder heads 21 and 22 respectively, are secured by dowels 23 and stud bolts 24. The upper cylinder head 21

30 is integrally formed with a support frame B and preferably ribs 25 are provided to reinforce the connection between the cylinder head and the frame. The upper portion 26 of the cylinder head 21 receives a steel bushing 27 with a drive fit, the lower margin 28 of the bushing extending to the inner face 29 of the upper cylinder head 21.

The driver sleeve F is rotatably supported within the bushing 27, and at its upper end is capped by a collar 30, held in fixed relation to the driver sleeve by a cap screw 31 threaded into a plug 32 which closes the upper end of the driver sleeve. The collar 30 has a shoulder 33 which receives the lower face of the motor rotor E, and the cap screw 31 bears against a washer 34 so that when the cap screw is tightened, the motor rotor E is clamped between the washer 34 and the shoulder 33 of the collar 30.

Obviously, the rigid connection between the motor rotor E and the driver sleeve F could be 45 accomplished by eliminating the collar 30 and having the rotor drive fitted on the sleeve F. All that is important here is that a rigid driving connection be established between the motor rotor E and the driver sleeve F.

50 The driver sleeve F is eccentrically bored to

receive the stud shaft or shank **H** which is rigid with the piston **G**.

It is important for an understanding of this invention to appreciate that the piston **G** and shank **H** are both circular in cross section and have the same center, whereas the driver sleeve **F** and cylinder ring **20** are concentric to each other, but eccentric to the piston **G** and shank **H**. It is, therefore, obvious that when the driver sleeve **F** is rotated by the motor rotor **E**, the shank **H** partakes of a circular movement which moves the piston around the inner circumference **35** of the cylinder ring **20**, as best shown in Figs. 2-5 inclusive. It will be noted that the point of tangency, generally indicated at **T**, moves around the cylinder in a clockwise direction assuming the motor is driven in that direction when looking down upon the pump.

The blade **I** divides the crescent-shaped pump chamber **36** into intake and discharge compartments of constantly varying size, that portion of the pump chamber lying clockwise between the blade **I** and the point of tangency being the intake chamber **37** and that portion lying clockwise between the point of tangency and the blade **I** being the discharge chamber **38**. The blade is rigidly secured to the cylinder ring **20** and the associated heads **21** and **22**, and has rocking and sliding engagement with the piston **G** by means of a rocker **39**. This arrangement is not only highly effective and desirable for partitioning the pump chamber, but it also holds the piston **G** against substantial rotary movement about its own axis, and as a result, reduces the wear between the piston and the cylinder ring.

The driver sleeve **F**, cylinder heads **21** and **22**, cylinder ring **20**, and rocker **39** are preferably made of nickel iron, while the bushing **21**, piston **G**, shank **H** and blade **I** are preferably of machine or tool steel, so that in all instances where two surfaces are in sliding engagement with each other, one of the surfaces is a hard steel, and the other a softer nickel iron.

The lower cylinder head **22** is provided with a protuberance **40** having a bore **41** which is concentric with the outer surface of the driver sleeve **F** and the inner surface of the cylinder ring **20**. A plug **42** of nickel iron is drive fitted into the bore **41** and the cap **43** of the plug constitutes a stationary member which forms one element of an oil pump generally designated **44** (Fig. 6). The lower face of the piston **G** is counterbored as best shown at **45** in Fig. 13 to receive the cap **43** in eccentric tangential relation, the counterbore **45** being concentric with the piston **G**. An extension **46** on the lower portion of the blade **I** is in close sliding engagement with the cap **43** (see Fig. 6) and as a result, the crescent-shaped space between the cap **43** and the walls of the counterbore **45** form a pump chamber for oil, the discharge portion of the chamber being indicated at **47** and the intake portion being indicated at **48**.

The blade **I** is rigidly clamped to the cylinder ring **20** and the associated cylinder heads so that it is effectively sealed by this rigid connection on three sides. The cylinder ring **20** is preferably split vertically to provide opposed portions **49** and **50**; and cap screws **51**, which pass through enlarged openings **52** in the blade, clamp the blade in place. Since it is important for the lower extension **46** on the blade to have a sealed fit with the cap **43** of the oil pump plug **42**, the blade is first mounted loosely between

the heads **21** and **22**, and is then forced inwardly until it makes proper engagement with the cap **43**, after which the blade screws **51** and head bolts **24** are tightened down to hold the adjustment.

The entire pump assembly is mounted within the dome **C** after first drive fitting the motor stator **53** into place against a seat **54** provided in the dome. The pump support frame **B** is then slid into place until it seats upon a shoulder **55** provided in the dome. A plurality of cap screws **56** securely fasten the frame to the dome.

The collar **30** is preferably provided with a counterweight **57** to balance the eccentricity of the planetary piston **G**. Being located on the opposite side from the support frame, the pump may be nicely balanced in this way, thus making the pump substantially free from vibration.

Preferably the counterweight is provided with a guide lug **58** which travels within a groove **59** provided in the stationary upper cylinder head **21**. In normal operation of the pump, the guide lug **58** runs free within the groove **59**, but should the pump be inverted for any reason, the lug **58** holds the motor rotor **E** in place so that return of the pump to normal position places the pump in immediate readiness for operation. The guide lug **58**, therefore, merely serves to prevent displacement of the parts when the pump is inverted.

The casing **C** is provided with a fitting, generally designated **60**, for receiving gas to be compressed by the pump **A**. The fitting is held in place on the dome by a cap screw **61**.

In the embodiment of the invention shown in Figs. 1 and 2, the dome is on the low side, that is, it is maintained at a pressure corresponding to the pressure of the gas prior to compression and the compressed gas is taken from the pump directly to the exterior of the dome. By using a low pressure dome, the pump parts may be kept cooler and forced draft over the compressor dome may be unnecessary. However, it should be understood that if desired, the pump may be constructed to operate with the dome on the high pressure side and with gas being delivered to the pump directly through a tube.

When the pump is operated on a low pressure dome, as shown in Figs. 1 and 2, the gas intake tube **62** is open to the dome and a similar tube **63** takes the gas from the dome and delivers it through a fitting **64**, screen **65**, intake valve generally designated **66**, and intake ports **67** to the intake chamber **37** of the main pump. The fitting **64** is threaded into the lower cylinder head **22** and the screen **65** is located within a chamber **68** provided in the lower head. (Fig. 7). The intake valve **66** is located within a chamber **69** provided in the ring **20** and communicates with the head chamber **68** through a passage **70**. A disk valve member **71** is held in place on a valve seat **72** by a steel ball **73** which is free to travel within a guideway **74** provided in the valve housing **75**. The housing is yieldingly urged against the lower cylinder head **22** by a spring **76**, although if desired, it may be rigidly held within the ring **20** by a drive fit. The housing has a plurality of openings **77** through which gas entering the housing through the valve **71** may pass to the chamber **69** and thence through the ports **67** into the intake chamber **37**. The weight of the ball **73** is sufficient to keep the valve closed at all times except when the pump is drawing gas into the chamber **37**.

As the point of tangency sweeps around the cylinder ring 20, the gas in the discharge chamber 38 is compressed until it reaches a pressure which opens the discharge valve generally designated 18. This valve comprises a housing 79 which is sealed against the flat wall 80 of the cylinder ring by means of a forked lever 81. The lever 81 is pivoted about one of the stud bolts 24 and has a forked end 82 (Figs. 2 and 8) which straddles the discharge elbow 83 and rests upon shoulders 84 to force the housing 79 into firm engagement with the wall 80 when the lever is rocked about its pivot 24 by a set screw 85.

The valve member 86 of the discharge valve is held against its seat 87 by a spring 88 which is selected with proper tension to open the valve at some given discharge pressure differential.

The discharge chamber 38 of the pump A communicates with the interior of the valve housing 79 through a passageway 89 and a tube 90 delivers the compressed gas to a fitting 91 which in turn is connected to suitable auxiliary equipment.

When the dome is operated on the high side of the pump, the tube 62 is connected directly to the nipple 64 of the intake valve and the tube 90 associated with the discharge valve is placed in communication with the interior of the dome, as is also the tube associated with the outlet connection 91.

Lubrication system

It is highly important in a pump of this kind to provide an adequate lubricating and sealing system, particularly when the dome is on the low side. This is true because the oil in a low side dome is under substantially constant pressure, whereas the pressure in the work chamber of the pump depends upon the load which the pump is carrying, and hence varies within wide limits. An oil pump, therefore, which delivers an adequate pressure for lubrication and sealing of the pump parts when the pump is operating under a given head pressure, may be totally inadequate or unsatisfactory when the head pressure is increased to some larger amount.

Even in pumps using a high side dome the use of the proper type of oil pump is highly important, and I, therefore, provide a lubricating and sealing system which is positive in its action and is capable of properly oiling and sealing the various pump surfaces regardless of the variations in head pressure on the main pump. This oiling system preferably includes a pump of the positive displacement type, or at least a pump which is capable of delivering oil for more than 50% of the pump cycle.

The dome C has an oil reservoir 92 in the bottom of the dome, the latter being closed by a bottom cover plate 93 which is secured to flanges 94 of the dome by a plurality of cap screws 95. An oil intake pipe 96 (Fig. 7) fitted at its end with a strainer 97 conducts oil from the reservoir to the counterbore, 41 in the lower cylinder head 22. A passageway 98 through the plug 42 connects the oil space below the plug with the intake chamber 48 of the oil pump 44. As the piston G partakes of planetary movement, the point of tangency T' between the plug cap 43 of the oil pump and the counterbore 45 in the piston G moves about the cap 43 in a clockwise direction (Fig. 6) thus causing oil to be forced from the chamber 47 through a discharge passage 99 in the plug 42, and through another discharge passage 100 which connects with arcuate grooves

101 and 102 on the lower and upper faces, respectively of the piston G, the two grooves being joined together at their ends by vertical bores 103 and 104.

For convenience in terminology, the cap 43 may be termed a piston and the counterbore 45, a cylinder, in describing the operation of the auxiliary oil pump even though in this instance, the piston is stationary and the cylinder is moved to produce a pumping action.

The positive displacement of oil by the oil pump 44 insures that a given quantity of oil will be moved through the various discharge passages for each cycle of the pump and adequate lubrication and sealing of the piston faces is thereby assured regardless of the head pressure on the main pump. The pump 44 will therefore deliver oil to the working clearances of the main pump at pressures well in excess of the work pressure in the main pump chamber.

A vertical bore 105 which extends through the piston G and into the piston shank H, has an enlarged mouth 106 which communicates at all times with the discharge passage 99 in the stationary cap 43 of the oil pump even though there is relative planetary motion between the piston G and the cap 43. Oil is, therefore, continuously delivered throughout substantially the entire pump cycle to the vertical bore 105 and supplied under continuous pressure in excess of work chamber pressure to the various work surfaces and bearing surfaces which must be lubricated and sealed. For example, a passageway 107 extends horizontally from the bore 105 to a groove 108 so that the rocker 39 may be properly lubricated and sealed. Also, a passage 109 extends laterally from the bore 105 to a relieved portion 110 in the piston shank H to permit oil to be forced upwardly and downwardly along the shank bearing surfaces. A passage way 111 communicates with the relieved portion 112 on the outer face of the driver sleeve F and this in turn communicates with a horizontal passage 113 in the support frame B which leads to an adjustable oil pressure relief valve 114 which may be adjusted to provide the desired head pressure in the oiling and lubricating system. The oil pump may be made smaller or larger to suit different head pressure conditions for which the main pump may be designed. Obviously, if the head pressure is too great, it will set up a back pressure that will detract from the overall efficiency of the pump, whereas if it is too small, the bearing surfaces and work surfaces in the pump chamber will not be adequately sealed against leakage.

It should be understood that the lubricating and sealing system which has been described has equal applicability to a pump which is housed within a dome that is on the high side of the main pump, although in such instances, other types of oil pumps such, for example, as gear pumps, centrifugal pumps, and other pumps which deliver oil for more than 50% of the operating cycle for the main pump, may be used with probably more effectiveness than would be the case were these oil pumps used with a low side dome.

In order to prevent undesirable oil pressures from being set up in the space 115 between the top of the piston shank H and the closure head 32 for the driver sleeve F, which pressure would tend to set up an end thrust on the shank H, a small relief passage 116 is provided through the plug 32 and collar 30, and a similar passage

117 is provided through the washer 34 so that the oil pressure within the chamber 115 will be substantially equal to dome pressure. Obviously, the oil escaping through the orifice 117, as well as all other oil which escapes from the bearings, or the relief passage 113, will fall to the oil reservoir 92 for re-use.

The motor leads 118 into the dome are preferably carried through the dome by a connector generally designated 119, as best shown in Fig. 2. The connector consists of a copper rod 120 having an enlarged central portion 121 backed on both sides by Duprene washers 122 which are clamped against the enlarged portion 121 by fiber insulators 123 which fit within a housing 124 welded onto the dome and closed by a threaded cap 125. The advantage of this arrangement is that should any leak develop through the connector, the cap 125 may be removed to replace the outer Duprene washer 122, this being accomplished without opening up the base 93 of the dome.

Modified form—Figs. 16 through 19, inclusive

In the modified form of the invention shown in Figs. 16 to 19 inclusive, a somewhat different arrangement is provided for driving the piston member while still retaining the advantages of having bearing areas for taking the force of compression which are greater in width than the width of the pump chamber and while retaining also the advantages of adequate lubrication and gas sealing.

Referring to Fig. 16, the pump assembly is mounted as before on a frame B within the dome C, but in this instance, the upper and lower cylinder heads 130 and 131 respectively are bored as shown at 132 and 133 respectively, to receive the oppositely extending shanks 134 of the planetary piston 135. The pump chamber 136 consists as before, of the crescent-shaped space that is defined by the upper and lower cylinder heads 130 and 131, the outer circumference of the piston 135 and the inner circumference of the cylinder ring 137. A partition blade 138 divides the pump chamber 136 into intake and discharge sides and is clamped in place within the cylinder ring by cap screws 139 and is similarly sealed against the top and bottom cylinder walls by the clamping action of the studs 140. The blade cooperates with a rocker 141 provided in the piston, as best shown in Figs. 16 and 18.

The piston is driven by a crank or eccentric 142 provided on the drive shaft 143 which is rigidly connected to the motor rotor 144. It will be noticed that the force of compression is distributed over the bearing area between the piston 135, with its extension shanks 134, and the crank 142, this bearing being considerably wider than the width of the pump chamber. Experience has shown that a bearing which is no wider than the pump chamber cannot adequately take the forces of compression.

The drive shaft 143 is journaled above the pump chamber in the upper cylinder head 130 and below the pump chamber in the lower cylinder head 131, and an oil pump generally designated 145 is operatively associated with the lower end of the drive shaft.

In this instance, the oil pump comprises a piston member 146 which is mounted in eccentric tangential relation to a bore 147 in the lower face of the cylinder head 131. The planetary movement of the piston 146 is imparted by a crank arm 148 at the lower end of the drive

shaft 143 and the work chamber 149 of the oil pump is divided into intake and discharge chambers by a blade 150 rigidly fixed by a pin 151 to a piston 146 and having rocking and sliding engagement with the stationary head 131 through a rocker 152. The oil intake into the work space 149 is indicated at 153 and the discharge for the oil pump is through a downwardly extending passageway 154 which communicates with an open space 155 formed below the shaft 143 in the bottom plate 156 which attaches to the lower face of the lower cylinder head 131.

Oil under pressure is transmitted through the space 155 to a vertical bore 157 in the shaft 143 from whence the oil is distributed to the piston bearing through channel 158; to the rocker bearing through channel 159; to the face grooves 160 and 161 in the piston through groove 162 and passages 163; and to the upper and lower shaft bearings through passages 164 and 165, respectively. An oil relief passage 166 is provided to prevent excess oil pressures from setting up undesirable back pressures which would have a tendency to increase the power required for operating the pump.

While the pump structure shown in Figs. 16 and 17 is preferred, another satisfactory type of pump is illustrated in Fig. 19 at 167. This pump is of the centrifugal type and consists of a rotor having a plurality of radially extending vanes 168, which take oil introduced into the pump centrally by an intake passage 169 and drive it outwardly by centrifugal action into the enlarged portion 170 of the cylindrical recess provided in the lower face of the cylinder head 131. The discharge passage for the oil pump is indicated at 171, and it communicates with the vertical bore 157 for distribution of oil to vital places, as shown in Fig. 16.

The rotor of the oil pump is rigidly attached to the drive shaft 143 by a screw 172 or other suitable means.

Preferably small oil relief passages 173 are provided in the heads 130 and 131 to prevent undesirable oil pressures from being built up in the bores 132 and 133.

It should be noted that all forms of the oil pumps herein shown and described are characterized by the fact that they deliver oil for more than 50% of their operating cycle, and by the further fact that they do not require the use of complicated valve structure, as is the case with reciprocating types of pumps.

Preferably the oil pump 145 shown in Figs. 16 and 17 is 90° out of phase with the main pump, i. e. the oil pump cycle is 90° in advance of the main pump cycle. The reason for this is to have the greatest volume of oil delivery coincide with the last 180° of the main pump cycle, when the work chamber pressure is highest and maximum sealing of the clearance spaces is required. The greatest volumetric delivery of oil from the pump 145 occurs as the point of tangency for the piston 146 moves clockwise from the position X to the position Y (Fig. 17), and for this maximum delivery to occur while the point of tangency for the main pump moves clockwise from the point X' to Y' (Fig. 18) it is necessary to have the crank 148 of the oil pump 90° in advance of the crank 142 of the main pump.

There is even some advantage when the oil pump is 180° out of phase as shown in the drawings because maximum delivery of oil then coincides with a substantial portion of the maximum pressure stage of the main pump.

To summarize in part some of the advantages of the pump structures which have been described, all of the pump structures are characterized by their ability to be made at relatively low cost, and to perform with outstanding efficiency. For example, the preferred embodiment of the invention shown in Figs. 1-15 inclusive has undergone tests which indicate that its power factor is far lower than competitive pumps now on the market. This remarkable performance is believed to be due to a combination of several features among which are the following:

(a) The use of a stationary fixed blade in the main pump which is rigidly sealed on three sides by the cylinder ring and the cooperating cylinder heads.

(b) The use of a rocker in the piston to accommodate the relative movement between the blade and the piston.

(c) The extended bearing for taking the force of compression, this bearing being greater in length than the width of the pump chamber.

(d) The use of fixed heads which cannot yield under compression pressure to permit leakage of gas from the discharge to the intake chambers of the pump.

(e) The use of a high pressure lubricating and sealing system which delivers oil to all clearance spaces of the pump parts at pressures in excess of work chamber pressure and which preferably includes oil pumps of the type which are characterized by delivering a stream of oil under pressure for more than 50% of the pump cycle and which do not require complicated valve structures.

I claim:

1. In a compressor, pump elements including a stationary headed-cylinder comprising an outer ring and end walls, and a piston within the cylinder mounted in eccentric tangential relation to the outer ring to form a crescent-shaped pump chamber, a blade dividing the chamber into intake and discharge stages, said blade being rigid with the outer ring and having a sealed fit with the end walls and ring, and a pivotally sliding sealed fit with the piston, inlet and outlet ports on opposite sides of the blade, driving means for moving the piston within the cylinder to produce a pumping action in the pump chamber, an auxiliary pump for delivering oil at pressures in excess of work pressures in the main pump chamber for more than one-half of the pumping cycle of the main pump including as pump members a cylinder formed in a recess in one of said elements and a piston in eccentric tangential relationship thereto, a blade for the auxiliary pump carried by one of the auxiliary pump members and engaging the other thereof dividing said recess into intake and discharge sections, said auxiliary pump being actuated with the main pump by the driving means therefor to produce a pumping action with relative movement between the piston and cylinder of the auxiliary pump, an intake for the auxiliary pump adapted to supply a lubricant thereto, and discharge passage means for delivering the lubricant from the auxiliary pump to the clearances between the elements of the main pump.

2. In a device of the class described, a main-pump comprising a stationary cylinder having heads rigidly fixed thereto and a piston within the cylinder mounted in eccentric tangential relation to form a pump chamber, a blade rigid with the cylinder and having a sealed fit with the end walls and cylinder, and a pivotally slid-

ing sealed fit with the piston for dividing the chamber into intake and discharge stages with intake and discharge ports in the respective stages, means for imparting a planetary movement to the piston to produce a pumping action in the pump chamber, and an oil pump for delivering oil at pressures in excess of work pressures in the main pump chamber for more than one-half of the pumping cycle of the main pump for lubricating and sealing the working clearances of the main pump, said oil pump including as pump members a cylinder and a piston in eccentric tangential relation thereto, means for closing the ends of the oil pump cylinder to provide a pumping chamber for the oil pump, and a blade carried by one of the oil pump members and engaging the other thereof dividing the oil pump chamber into intake and discharge stages, said oil pump being actuated by the driving means for the main pump to produce a pumping action with relative movement between the piston and cylinder of the oil pump, an intake for the oil pump adapted to supply lubricant thereto, and discharge passage means for delivering the lubricant from the oil pump to the working clearances of the main pump.

3. In a rotary pump, pump members including a hollow cylindrical member, a piston member mounted therein in eccentric tangential relation, end plates rigid with one of said members and defining with both members a pump chamber, a partition for the chamber associated with the end plates and the member to which they are secured, said partition being immovably fixed relatively thereto, inlet and outlet ports on opposite sides of the partition, one of said pump members being stationary and the other movable, driving means for causing the movable pump member to move relative to the stationary member to produce a pumping action within the pumping chamber, and an auxiliary pump for supplying lubricant under pressure in excess of that within the pump chamber of the main pump to the working clearances thereof, said auxiliary pump comprising as pump members a cylinder and a piston mounted in eccentric tangential relation thereto, means for closing the ends of the cylinder to form with the cylinder and piston an auxiliary pump chamber, and a blade for the auxiliary pump constituting an integral part of the partition for the main pump and carried by one of the auxiliary pump members and engaging the other thereof to divide the auxiliary pump chamber into intake and discharge sections, said auxiliary pump being actuated with the main pump by said driving means to produce a pumping action with relative movement between the piston and cylinder of the auxiliary pump, an oil intake to the auxiliary pump, and means for delivering oil from the auxiliary pump to the working clearances of the main pump.

4. In a rotary pump, pump members including a hollow cylindrical member, a piston member mounted therein in eccentric tangential relation, end plates rigid with one of said members and defining with both members a pump chamber, a partition for the chamber associated with the end plates and the member to which they are secured, said partition being immovably fixed relatively thereto, one of said pump members being stationary and the other movable, inlet and outlet ports on opposite sides of the partition, driving means for causing the movable pump member to move relative to the stationary member to produce a pumping action within the pumping cham-

ber, and an auxiliary pump having inlet and discharge passages for supplying oil at pressures in excess of work pressures in the main pump chamber to the working clearances of the main pump, said auxiliary pump being of the rotary type and being characterized by its ability to deliver oil at said pressures to said clearances for more than half of the pumping cycle of the main pump.

5. In a device of the class described, a main pump comprising a stationary cylinder, a piston therein mounted in eccentric tangential relation, end plates rigid with the cylinder to define with the cylinder and piston a main pump chamber, a partition blade fixed to the cylinder and end plates and having rocking and sliding engagement with the piston, inlet and outlet ports on opposite sides of the blade, a rigid shank on the piston extending laterally beyond the inner pump chamber face of the adjacent end plate to provide a bearing surface of ample length to directly take the force of compression, driving means engaging said bearing surface for moving the piston within the cylinder to produce a pumping action in the pump chamber, and an oil pump actuated by said driving means for delivering oil under pressure in excess of that within the main pump chamber to the working clearances of the main pump, said oil pump being of the rotary type and being characterized by its ability to deliver oil to said working clearances at said pressures for more than half of the pumping cycle for the main pump.

6. In a device of the class described, a main pump comprising a stationary cylinder, a piston therein mounted in eccentric tangential relation, end plates rigid with the cylinder to define with the cylinder and piston a main pump chamber, a partition blade fixed to the cylinder and end plates and having rocking and sliding engagement with the piston, inlet and outlet ports on opposite sides of the blade, a rigid shank on the piston extending laterally beyond the inner pump chamber face of the adjacent end plate to provide a bearing surface of ample length to directly take the force of compression, driving means engaging said bearing surface for moving the piston within the cylinder to produce a pumping action in the pump chamber, and an oil pump actuated by said driving means for delivering oil under pressure in excess of that within the main pump chamber to the working clearances of the main pump, said oil pump being of the rotary type and being characterized by its ability to deliver oil to said working clearances at said pressures for more than half of the pumping cycle for the main pump, said oil pump being further characterized by having intake and discharge stages which are in open communication with intake and discharge passages leading to the oil pump.

7. In a rotary pump, pump members including a hollow cylindrical member, a piston member mounted therein in eccentric tangential relation, end plates rigidly secured to one of said members to form with the other a pump chamber, a partition for the chamber associated with the end plates and the member to which they are secured, said partition being immovably fixed relatively thereto, one of said pump members being stationary and the other movable, inlet and outlet ports on opposite sides of the partition, driving means for causing the movable pump member to move relative to the stationary pump member to produce a pumping action within the pump chamber, and bearing means including a shank rigid with the movable pump member and extending

5 outside of the space between the end plates whereby ample support may be provided for the shank to directly take the force of compression, said bearing means having a total length which is substantially in excess of the width of the pump chamber, and an auxiliary pump for delivering oil at pressures in excess of work pressures in the main pump chamber for more than one-half of the pumping cycle of the main pump for supplying lubricant under pressure to the working clearances of the main pump, said auxiliary pump including as pump members a cylinder, a piston in eccentric tangential relationship thereto and a blade for the auxiliary pump carried by one of the auxiliary pump members and engaging the other thereof dividing the auxiliary pump chamber into intake and discharge sections, said auxiliary pump being actuated with the main pump by said driving means to produce a pumping action with relative movement between the piston cylinder and the auxiliary pump, an intake for supplying lubricant to the auxiliary pump, and discharge passage means for delivering the lubricant from the auxiliary pump to the working clearances of the main pump.

8. In a rotary pump, a gas tight dome, pump members including a hollow cylindrical member, a piston member mounted therein in eccentric tangential relation, end plates rigid with one of said members and defining with both members a pump chamber, a partition for the chamber associated with the end plates and the member to which they are secured, said partition being immovably fixed relatively thereto, one of said 30 pump members being stationary and the other movable, inlet and outlet ports on opposite sides of the partition, driving means for causing the movable pump member to move relative to the stationary member to produce a pumping action 35 within the pumping chamber, and an auxiliary pump for supplying lubricant under pressure in excess of that within the pump chamber of the main pump to the working clearances thereof, said auxiliary pump comprising as pump members a cylinder and a piston mounted in eccentric tangential relation thereto, means for closing the ends of the cylinder to form with the cylinder and piston an auxiliary pump chamber, and a blade for the auxiliary pump carried by one of the auxiliary pump members and engaging the other thereof to divide the auxiliary pump 40 chamber into intake and discharge sections, said auxiliary pump being actuated with the main pump by said driving means to produce a pumping action with relative movement between the piston and cylinder of the auxiliary pump, an oil intake to the auxiliary pump, and means for delivering oil from the auxiliary pump to the working clearances of the main pump, said dome being in open communication with the intake 45 stage of the main pump.

9. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having 50 rocking and sliding engagement with the piston, inlet and outlet ports on opposite sides of the blade, driving means for moving the piston relative to the cylinder to produce a pumping action, and an auxiliary pump associated with the main pump for delivering oil at pressures in excess of

working pressure within the main pump chamber to lubricate and seal the working clearances of the main pump, said auxiliary pump including as pump members a cylinder member and a piston member mounted therein in eccentric tangential relation, one of said members being rigid with the stationary cylinder of the main pump, and the other of said members being rigid with the piston of the main pump, means for closing the ends of the auxiliary pump cylinder to form a work chamber, means dividing the auxiliary pump work chamber into intake and discharge stages, an intake for supplying oil to the auxiliary pump, discharge means for delivering oil from the auxiliary pump to the working clearances of the main pump, said auxiliary pump being actuated by the driving means for the main pump.

10. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston, inlet and outlet ports on opposite sides of the blade, means for imparting a planetary movement to the piston member whereby a pumping action is produced within the pump chamber, said means including a laterally extending shank rigid with the piston and a driver in telescopic engagement with the shank and having its axis of rotation eccentric to the axis of the shank, and an auxiliary pump associated with the main pump for delivering oil under pressure in excess of main pump head pressure to the working clearances of the main pump, said auxiliary pump including as pump members a cylinder member and a piston member mounted therein in eccentric tangential relation, one of said members being rigid with the stationary cylinder of the main pump, and the other being rigid with the piston of the main pump, means for closing the ends of the auxiliary pump cylinder to form a work chamber, means dividing the auxiliary pump chamber into intake and discharge stages, an intake for supplying lubricant to the auxiliary pump, discharge means for delivering lubricant from the auxiliary pump to the working clearances of the main pump, and means for actuating the auxiliary pump by the driving means for the main pump.

11. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston, inlet and outlet ports on opposite sides of the blade, driving means for imparting to the piston a planetary movement to produce a pumping action in the pump chamber, said driving means including a shank rigid with the piston and projecting laterally to one side of the pump, a driver sleeve eccentrically telescoped over the shank and adapted when rotated about its own center to impart to the piston through the shank a planetary motion within the cylinder to produce a pumping action, and an auxiliary pump associated with the main pump for delivering oil under pressure in excess of main pump head

pressure to the working clearances of the main pump, said auxiliary pump including as pump members a cylinder member and a piston member mounted therein in eccentric tangential relation, one of said members being rigid with the stationary cylinder of the main pump, and the other being rigid with the piston of the main pump, means for closing the ends of the auxiliary pump cylinder to form a work chamber, means dividing the auxiliary pump chamber into intake and discharge stages, an intake for supplying lubricant to the auxiliary pump, discharge means for delivering lubricant from the auxiliary pump to the working clearances of the main pump, and means for actuating the auxiliary pump by the driving means for the main pump.

12. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, inlet and outlet ports on opposite sides of the blade, said blade having rocking and sliding engagement with the piston, driving means for imparting to the piston a planetary movement to produce a pumping action in the pump chamber, said driving means including a shank rigid with the piston and projecting laterally to one side of the pump, a driver sleeve eccentrically telescoped over the shank and adapted when rotated about its own center to impart to the piston through the shank a planetary motion within the cylinder to produce a pumping action, and an auxiliary pump associated with the main pump for delivering oil at pressures in excess of working pressure within the main pump chamber to lubricate and seal the working clearances of the main pump, said auxiliary pump including a cylindrical recess in the face of the piston remote from the shank, a piston rigid with the stationary cylinder of the main pump mounted in eccentric tangential relation to the cylindrical recess, means for closing the ends of the auxiliary pump to form a work chamber, an intake for supplying lubricant to the auxiliary pump, discharge means for delivering oil from the auxiliary pump to the working clearances of the main pump, and means for dividing the auxiliary pump chamber into intake and discharge stages communicating with said oil intake and discharge means respectively whereby planetary movement of the main pump piston within the main pump cylinder will produce a pumping action within the auxiliary pump for delivering oil through said auxiliary pump discharge means.

13. In a rotary pump, pump means including a hollow cylindrical member, a piston member mounted therein in eccentric tangential relation, end plates rigidly secured to one of said members to form with the other a pump chamber, a partition for the chamber associated with the end plates and the member to which they are secured, said partition being immovably fixed relatively thereto and having rocking and sliding engagement with the other member, inlet and outlet ports on opposite sides of the partition, means for producing relative movement between the pump members to produce a pumping action within the pump chamber, and an auxiliary pump operatively associated with the main pump, said auxiliary pump including as pump

members a cylinder and a piston mounted in eccentric tangential relation thereto to form with end closures a pump chamber therebetween, means for dividing the auxiliary pump chamber into intake and discharge stages including a portion of said main pump partition having a close running fit with the auxiliary pump piston, inlet and outlet ports on opposite sides of said dividing means and means for adjustably positioning the main pump partition in proper running relation to the auxiliary pump piston and thereafter locking said partition to the end plates of the main pump and the main pump member to which said end plates are secured.

14. In a rotary pump, a gas-tight dome, a motor stator mounted within the dome, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston, inlet and outlet ports on opposite sides of the blade, driving means for imparting to the piston a planetary movement to produce a pumping action in the pump chamber, said driving means including a shank rigid with the piston and projecting laterally to one side of the pump, a driver sleeve eccentrically telescoped over the shank and adapted when rotated about its own center to impart to the piston through the shank a planetary motion within the cylinder to produce a pumping action, a motor rotor carried by the driver sleeve, a bearing on one of the cylinder heads overlapping the telescopic engagement of the driver sleeve and shank, a support frame rigidly attached to said cylinder head bearing for supporting the entire pump assembly within the dome, and an auxiliary pump associated with the main pump for delivering oil under pressure in excess of main pump head pressure to the working clearances of the main pump, said auxiliary pump including as pump members a cylinder member and a piston member mounted therein in eccentric tangential relation, one of said members being rigid with the stationary cylinder of the main pump and the other being rigid with the piston of the main pump, means for closing the ends of the auxiliary pump cylinder to form a work chamber, means dividing the auxiliary pump chamber into intake and discharge stages, an intake for supplying lubricant to the auxiliary pump, discharge means for delivering lubricant from the auxiliary pump to the working clearances of the main pump, and means for actuating the auxiliary pump by the driving means for the main pump.

15. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston, inlet and outlet ports on opposite sides of the blade, driving means for moving the piston relative to the cylinder to produce a pumping action within the pump chamber, said driving means including a shaft extending through

the piston and having an eccentric in telescopic engagement with a central bearing on the piston, said bearing including a laterally projecting shank on the piston extending beyond one of the inner faces of the cylinder heads and providing a bearing surface having greater axial length than the width of the pump chamber, and an auxiliary pump associated with the main pump for delivering oil under pressure to lubricate and seal the working clearances of the main pump, said auxiliary pump being of the rotary type and characterized by its ability to supply lubricant to said working clearances for more than half of the main pump cycle.

15. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston inlet and outlet ports on opposite sides of the blade, driving means for moving the piston relative to the cylinder to produce a pumping action within the pump chamber, said driving means including a shaft extending through the piston and having an eccentric in telescopic engagement with a central bearing on the piston, said bearing including a laterally projecting shank on the piston extending beyond one of the inner faces of the cylinder heads and providing a bearing surface having greater axial length than the width of the pump chamber, and an auxiliary pump associated with the main pump for delivering oil under pressure in excess of main pump head pressure to lubricate and seal the working clearances of the main pump, said auxiliary pump including as pump members a cylinder member and a piston member mounted in eccentric tangential relation, means for closing the ends of the auxiliary pump cylinder to form a work chamber, means for dividing the auxiliary pump chamber into intake and discharge stages, and means including the drive shaft for imparting relative movement between the cylinder and the piston of the auxiliary pump to produce a pumping action within the auxiliary pump chamber, an intake for supplying lubricant to the auxiliary pump, and discharge means for delivering oil from the auxiliary pump to the working clearances of the main pump.

17. In a rotary pump, a main pump comprising a stationary cylinder, a piston mounted therein in eccentric tangential relation, heads rigidly fixed to the cylinder and defining with the cylinder and the piston a main pump chamber, a blade rigidly attached to the cylinder and the heads for dividing the main pump chamber into intake and discharge stages, said blade having rocking and sliding engagement with the piston, inlet and outlet ports on opposite sides of the blade, driving means for moving the piston relative to the cylinder to produce a pumping action within the pump chamber, said driving means including a shaft extending through the piston and having an eccentric in telescopic engagement with a central bearing on the piston, said bearing including a laterally projecting shank on the piston extending beyond one of the inner faces of the cylinder heads and providing a bearing surface having greater axial length than the width of the pump chamber, and an auxiliary pump associated with the main

pump for delivering oil under pressure in excess of main pump head pressure to lubricate and seal the working clearances of the main pump, said auxiliary pump including as pump members a cylinder member and a piston member mounted in eccentric tangential relation, means for closing the ends of the auxiliary pump cylinder to form a work chamber, means for dividing the auxiliary pump chamber into intake and discharge stages, and means including the drive shaft for imparting relative movement between the cylinder and the piston of the auxiliary pump to produce a pumping action within the auxiliary pump chamber, an intake for supplying lubricant to the auxiliary pump, and discharge means for delivering oil from the auxiliary pump to the working clearances of the main pump, the auxiliary pump having a phase relationship to the main pump which causes the greatest volume of oil to be delivered to the working clearances of the main pump when the pressure in the main pump chamber is highest.

18. In a rotary pump, pump members including a hollow cylindrical member, a piston member mounted therein in eccentric tangential relation therewith, end plates rigidly secured to one of said members to form with the other a pump chamber, a partition for the chamber associated with the end plates and the member to which they are secured, said partition being immovably fixed relatively thereto, one of said pump members being stationary and the other movable, driving means for causing the movable pump member to move relative to the stationary member to produce a pumping action within the pump chamber, said driving means including a shaft having an eccentric, said movable pump member having an axial internal bearing surface for the eccentric, a hollow shank rigid with the movable pump member and projecting outwardly through one of the end plates to provide an extension of said internal bearing surface, the total length of the bearing surface in engagement with the eccentric being substantially in excess of the width of the pump chamber.

19. In a rotary pump, pump members including a hollow cylindrical member, a piston member mounted therein in eccentric tangential relation therewith, end plates rigidly secured to one of said members to form with the other a pump chamber, a partition for the chamber associated with the end plates and the member to which they are secured, said partition being immovably fixed relatively thereto, one of said pump members being stationary and the other movable, driving means for causing the movable pump member to move relative to the stationary member to produce a pumping action within the pump chamber, said driving means including an axial internal bearing surface in the movable pump member, a drive shaft extending through the movable pump member and having an eccentric in engagement with said bearing surface, a hollow shank rigid with the movable pump member projecting outwardly through one of the end plates and providing an extension of the internal bearing surface, the total length of the bearing surface in engagement with the eccentric being substantially in excess of the width of the pump

chamber, and means for journaling the drive shaft on both sides of the eccentric.

20. In a rotary pump, pump members including a hollow cylindrical member, a piston member mounted therein in eccentric tangential relation therewith, end plates rigidly secured to one of said members to form with the other a pump chamber, a partition for the chamber associated with the end plates and the member to which they are secured, said partition being immovably fixed relatively thereto, one of said pump members being stationary and the other movable, driving means for causing the movable pump member to move relative to the stationary member to produce a pumping action within the pump chamber, said driving means including a shaft having an eccentric, said movable pump member having an axial internal bearing surface for the eccentric, a hollow shank rigid with the movable pump member and projecting outwardly through one of the end plates to provide an extension of said internal bearing surface, the total length of the bearing surface in engagement with the eccentric being substantially in excess of the width of the pump chamber, and an oil pump driven by the same power that drives the main pump and having an inlet port and one or more discharge passages leading to at least some of the working clearances of the main pump, said oil pump being characterized by its ability to supply oil to said working clearances at sufficiently high pressures to effectively seal the main pump against leakage of the fluid being operated on.

21. In a rotary pump, pump members including a hollow cylindrical member, a piston member mounted therein in eccentric tangential relation therewith, end plates rigidly secured to one of said members to form with the other a pump chamber, a partition for the chamber associated with the end plates and the member to which they are secured, said partition being immovably fixed relatively thereto, one of said pump members being stationary and the other movable, driving means for causing the movable pump member to move relative to the stationary member to produce a pumping action within the pump chamber, said driving means including an axial internal bearing surface in the movable pump member, a drive shaft extending through the movable pump member and having an eccentric in engagement with said bearing surface, a hollow shank rigid with the movable pump member projecting outwardly through one of the end plates and providing an extension of the internal bearing surface, the total length of the bearing surface in engagement with the eccentric being substantially in excess of the width of the pump chamber, means for journaling the drive shaft on both sides of the eccentric, and an oil pump driven by the same power that drives the main pump and having an inlet port and one or more discharge passages leading to at least some of the working clearances of the main pump, said oil pump being characterized by its ability to supply oil to said working clearances at sufficiently high pressures to effectively seal the main pump against leakage of the fluid being operated on.

WILLIAM WARD DAVIDSON.
